HANDLE

Hugo M. Litterio, Providence, R. I.

Application March 29, 1948, Serial No. 17,759

1 Claim. (Cl. 279—35)

1

This invention relates to improvements in handles, and more particularly to the provision of a handle adapted to tightly hold files while in use.

The usual handle for files has a wedge shaped elongated hole which becomes enlarged with frequent use of the file and the file is not tightly held in place. On the other hand, when the file is tightly held in place, it is difficult to remove the file to insert another file.

It is, therefore, an object of this invention to provide a handle which will tightly hold a file at all times when, the motions of the file while doing work tending to increase the grip of the handle on the file.

A further object is to provide a handle for files provided with means to enable a file to be easily and quickly removed when so desired.

A further object is to provide a handle for files which is made of two similar parts, easily assembled, and providing a good grip.

These and other objects are attained by the novel construction and arrangement of parts hereinafter described and illustrated by the accompanying drawings, forming a part hereof, and in which:

Fig. 1 is a sectional view of a file handle embodying the invention.

Fig. 2 is a top view of the handle.

Referring to the drawings, the handle for files is shown to be made in two similar sections, each of which has an internal flat surface 1, and an outer rounded portion to form a hand grip. Since the sections are identical, only one need be described.

Referring to Fig. 1, section surface 1 is shown to have a recess 2 in which are pivotally mounted by means of pivot pins 5 and 6, the levers 3 and 4. Each lever has an upper inclined face 7 and a lower inclined face 8, the portion of the lever carrying face 7 being shorter than the portion of the lever carrying the face 8, so that as the tapered end of a file moves down in the recess it will engage the faces 8 to cause the levers to rotate and move the faces 7 tightly against the upper portions of the tapered part of the file.

The recess 2 communicates with an elongated recess 9 in which is positioned a head 10 adapted to rest on a shoulder 13 at the lower part of recess 9. Integral with and extending down

2

from the head 10 is a pin 11 which moves in a reduced extension of recess 9. The pin 11 is encircled by a coiled compression spring 12 which bears against a shoulder 14 and also bears against the head 10 normally tending to move the head 10 upward.

The two sections of the handle are secured together by means of rivets, bolts, or the like as denoted at 15.

10 In operation, the tapered end of the file is forced down between the inclined heads or faces 7 and 8 of levers 3 and 4, until the grip of the faces on the tapered end becomes so great that further downward movement is prevented. The inclined faces 7 are longer than the inclined faces 8 so that when a file in the holder engages faces 7, the faces 8 are rotated into a position to tightly grip the tapered portion of the file and also causing a tight grip by the faces 7.

20 The spring 12 will urge the head 10 upward until it engages the tip of the tapered portion of the file as shown in Fig. 1, the compression of the spring insuring firm engagement of the head and tip. When it is desired to remove the file, it is only necessary to strike the pin 11 with a tool or against a hard surface, which will move the file upward from engagement with the inclined faces 7 and 8. Obviously, the length of the pin and spring can be arranged to properly accommodate tapered file ends of various lengths.

25 While the levers 3 and 4 have been shown to have square corners, obviously they may be rounded, the same leverage taking place regardless of shapes of the levers.

30 The handle can be made of a light weight metal such as aluminum or it can be made of wood, plastics, and similar materials commonly used for handles.

35 The above description is to be considered as 40 illustrative and not limitative of the invention of which modifications can be made without departing from the spirit of the invention as set forth in the appended claim.

The invention having been described, what is 45 claimed is:

A handle for holding files, comprising two sections of similar shape, each section having at its upper end a recess communicated with an elongated recess in the lower end, said elongated recess having a reduced extension, a pair of op-

posed levers spaced from each other and pivotally mounted in the upper recess, each lever having an inclined upper face and an inclined lower face, said inclined lower face projecting further into the recess than the upper inclined face, a shoulder in the handle at the lower portion of the main part of the elongated recess, a head adapted to rest on the shoulder, a compression spring engaging the head and normally tending to move the head towards the levers, a pin connected to the head and encircled by the spring, said pin passing through the extension to the elongated recess, and a shoulder upon which the lower end of the spring rests.
